UNITED STATES PATENT OFFICE.

JOHN KIERNAN, OF PATERSON, NEW JERSEY.

PROPELLER APPARATUS FOR VESSELS.

1,158,929.

Specification of Letters Patent.

Patented Nov. 2, 1915.

Application filed April 23, 1915. Serial No. 23,300.

To all whom it may concern:

Be it known that I, JOHN KIERNAN, a citizen of the United States, and residing at Paterson, in the county of Passaic and State of New Jersey, have invented certain new and useful Improvements in Propeller Apparatus for Vessels, of which the following is a specification, such as will enable those skilled in the art to which it appertains to make and use the same.

This invention relates to power apparatus or propelling mechanism for vessels, and the object thereof is to provide an improved apparatus of this class in which the propelling medium or power agent is compressed air, and in which the compressed air is automatically supplied after the apparatus has once been started and the vessel put in motion, and with this and other objects in view the invention consists in an apparatus of the class specified, constructed and operated as hereinafter described and claimed.

The invention is fully disclosed in the following specification, of which the accompanying drawing forms a part, in which the separate parts of my improvement are designated by suitable reference characters in each of the views, and in which:

Figure 1 is a sectional plan view of the hull of a vessel provided with my improved propelling apparatus; Fig. 2 a cross section on the line 2—2 of Fig. 1 and showing a detail of the construction; and, Fig. 3 a view looking in the direction of the arrow 3 of Fig. 1 and showing another detail.

In the drawing forming part of this specification, I have shown at *a* the hull of a vessel which, in the form of construction shown, is provided with two transverse bulkheads *a*² having bulkhead doors *a*³ and dividing the hull into three separate compartments *a*⁴, *a*⁵ and *a*⁶, but it must be understood that my invention is not limited to the number of bulkheads, or the number of compartments, any desired number of which may be employed.

In the practice of my invention I place horizontally of the hull and in the bottom portion thereof, and on the opposite side of the keel thereof, two pipes *b* which open forwardly through the bow of the hull and backwardly through the stern thereof, and in connection with these pipes are mounted both in the bow portion and stern portion, a pair of water driven motors or turbines *c*, one for each pipe, and these pairs of water

driven motors have a common shaft *c*² provided centrally thereof with a small gear wheel *c*³, and the gear wheels *c*³ mesh with larger gears *c*⁴ mounted on crank shafts *c*⁵ inwardly of the motors *c*, and inwardly of the crank shafts *c*⁵ are mounted compressors *c*⁶ driven by the crank shafts *c*⁵, and the compressors *c*⁶ are connected by pipes *c*⁷ with a common compressed air tank or receiver *c*⁸, and the pipes *c*⁷ are provided with valves *c*⁹.

At one side of the air tank *c*⁸ is a compressor *d* driven by a gasoline, electric or other motor *d*², and the compressor *d* is placed in communication with the tank *c*⁸ by a pipe *d*³ provided with a valve *d*⁴.

Connected with the tank *c*⁸ is a pipe *e* having a valve coupling *e*² and the pipe *e*, tank *c*⁸ and compressor *d*, in the construction shown, are located in the central compartment *a*⁵, and the valve coupling *e*² is provided with a valve *e*³ operated by a rod *e*⁴ which passes through the bulk-head *a*², and is adapted to be operated from the rear compartment *a*⁴, and said pipe *e* is also provided with a transverse pipe *e*⁵ which passes through both of the bulkheads *a*² and communicates with the compartments *a*⁴ and *a*⁶, and the pipe *e*⁵ is provided with two valves *e*⁶ and *e*⁷ operated respectively by rods *e*⁸ and *e*⁹ which also pass through the rear bulkhead *a*² into the compartment *a*⁴, and for the purpose of this description the engine room may be said to be located in the compartment *a*⁴.

The pipes *b* are provided near both ends, or forwardly and backwardly of the corresponding motor *c* with valve devices *f* operated by gears *f*² geared in connection by sprocket chains *f*³, and the sprocket chains *f*³ are driven by a central gear *f*⁴ and connected with the gear *f*⁴ are other gears *f*⁵, and mounted on the gears *f*⁵ are drive chains *f*⁶, and the drive chains *f*⁶ of the front valve devices *f* extend back into the engine room and both of said drive chains *f*⁶ also pass around gears *f*⁷ having cranks *f*⁸ by which they may be operated, and by means of this construction the valve devices *f* at the front or bow of the vessel may be regulated or controlled at all times from the engine room as may also the valve devices *f* at the stern of the vessel.

The vessel is driven by a propeller *g* having a shaft *g*² which passes into and is driven by a compressed air engine *g*³, and

said propeller shaft is provided with a balance wheel g^4 and a pipe g^5 is connected with the compressed air tank c^8 and with the compressed air engine g^3 and is provided with valves g^6 and g^7 , one of which is in the rear compartment of the vessel, or the engine room, and the other in the central compartment. I also provide a compressed air gage h which is mounted in the engine room and is in communication with the compressed air tank c^8 by a pipe h^2 which passes through the rear bulkhead a^2 .

With this construction the tank c^8 is first filled with compressed air by the engine or motor d^2 and the propeller is started by opening the valves g^6 and g^7 , or the pipe g^5 may be provided with but one valve, if desired, and as the propeller is started the valves f both in the front and stern portions of the vessel are open and the water rushes through the pipes b and operates the motors c , and the air in the tank c^8 is automatically compressed, or said tank is kept filled with compressed air automatically, and the compressed air from the tank c is automatically supplied to the engine g^3 , and this continues as long as the vessel is in motion. It will therefore be seen that the compressor d may be used only for starting the engine or apparatus, after which the valve d^4 may be closed and the operation will be automatic, but the said compressor d may be employed whenever necessary for the purpose of filling or refilling the tank c^8 , but under all normal conditions the operation of the water passing through the pipes b and driving the motor c will operate the compressor c^6 and keep the tank c^8 supplied with air under sufficient pressure to drive the engine g^3 . It will also be seen that the separate compartments a^4 , a^5 and a^6 of the hull may be kept full of compressed air from the tank c^8 , and this pressure may be increased whenever desired and may be made sufficient in case of injury to the hull to prevent water from entering either of said compartments. It will also be understood that my invention is not limited to the exact details of construction, combination, and arrangement of parts herein shown and described, and various parts of my improved propelling apparatus may be located in any desired position, and various changes in and modifications of the construction herein described may be made, within the scope of

the appended claims, without departing from the spirit of my invention or sacrificing its advantages.

Having fully described my invention, what I claim as new and desire to secure by Letters Patent, is:

1. A vessel, the bottom of the hull of which is provided with two pipes which extend longitudinally therethrough and which open through the bow and stern of the hull, 65 water motors adapted to be driven by water passing through said pipes, a main air tank, means whereby the operation of said motors will fill said tank with compressed air, independent means for filling said tank with 70 compressed air, and a propeller driven by compressed air taken from said tank.

2. A vessel, the bottom of the hull of which is provided with two pipes which extend longitudinally therethrough and which open through the bow and stern of the hull, 75 water motors adapted to be driven by water passing through said pipes, a main air tank, means whereby the operation of said motors will fill said tank with compressed air, 80 independent means for filling said tank with compressed air, a propeller driven by compressed air taken from said tank, and means for controlling the passage of water through said pipes.

3. A combination with the hull of a vessel of bulkheads by which said hull is divided into separate compartments, parallel pipes mounted longitudinally in the bottom of the hull and opening through the bow and stern 90 thereof and passing through said bulkheads, a compressed air tank, means for filling said tank with compressed air, motors connected with said pipes and operated by water passing therethrough, means whereby the operation of said motors will also compress the air in said tank, a propeller driven by compressed air taken from said tank, and means whereby the compartments of the hull may be filled with compressed air taken from 100 said tank.

In testimony that I claim the foregoing as my invention I have signed my name in presence of the subscribing witnesses this 21st day of April 1915.

JOHN KIERNAN.
